By Brown, Nissen & Sprinkle Atty's.

UNITED STATES PATENT OFFICE.

EPHRAIM H. BODEN, OF CHICAGO, ILLINOIS.

CALENDAR.

1,289,220.

Specification of Letters Patent.

Patented Sept. 4, 1917.

Application filed October 8, 1915. Serial No. 51,297.

To all whom it may concern:

Be it known that I, EPHRAIM H. BODEN, a citizen of the United States, residing at Chicago, in the county of Cook and State 5 of Illinois, have invented certain new and useful Improvements in Calendars, of which the following is a specification.

My invention relates to calendars, and has for its object the provision of a simple 10 and efficient calendar made up of the fewest number of complete calendar months possible, with an index indicating the particular month calendar any desired date appears on. Other objects will appear herein- 15 after.

An embodiment of my invention is illustrated in the accompanying drawing forming a part of this specification, and in which—

20 Figure 1 is a set of seven month calendars used in my calendar, and

Fig. 2 is an index used in conjunction with the month calendars.

My calendar is particularly adaptable 25 for the class of calendars termed perpetual calendars, and may be easily arranged by any one familiar with my invention. I preferably use seven month calendars, each being made up of thirty-one days numbered "1" to "31" inclusive, and the different month calendars arranged so that each begins on a different day of the week from the others. Since some months of the year have fewer than thirty-one days, 30 I prefer to designate the numerals "29", "30" and "31" in each of the month calendars in a distinctive manner from each other and from numerals "1" to "28" inclusive. In the drawing I have done this by placing 35 a different number of lines under each of the numerals "29", "30" and "31". In practice this may be done by using different colored inks or different faces of types, as will be readily understood by those skilled 40 in the art. In order to further attract the user of my calendar to the particular number of days to be used in any of the month calendars, I preferably use the notice shown at the bottom of the drawing, or its equivalent. This, together with the distinctive 45 manner of writing the numerals "29", "30" and "31", will render the use of any particular calendar month obvious to any one.

I preferably use a designating symbol at 50 the head of each of the month calendars. In the drawing I have used numerals which

correspond to the day in the week on which the calendar months begin. It will be understood that other designating symbols may be used in naming or designating the 60 calendar months, but whatever symbols are used, such symbols should have a well recognized consecutive order, so that one will know at once the day of the week upon which any calendar month begins by 65 seeing the symbol.

I provide an index which is made up of a column of consecutive year dates, which may extend over any desired number of years. Following the column of year dates, 70 I provide twelve columns of symbols, and at the head of each of the columns is provided the name of one of the months of the calendar year. The month columns are made up of the symbols which designate the 75 month calendars. In the drawing it will be noted that the month columns are each made up of numerals "1" to "7" inclusive, and that these symbols have a somewhat regular order in which they appear. In the 80 January and February month columns, between each leap year and the year following it one symbol is dropped from the regular consecutive order of the symbols, and in the other ten month columns one symbol is 85 dropped between each of the leap years and the year immediately before it. With this simple rule in mind the symbols are arranged for indicating the desired month 90 calendars in which any desired date will appear.

In making up the index of my calendar, it is first necessary to know the particular day of the week on which each of the months in a particular year begins. When this is 95 done the proper symbols are set down in the month columns, then each of the month columns built up from the symbol set down in its particular column. For instance, we may take the year 1915, and in it we find in 100 the January month column the numeral "6", which is the symbol relating to the month calendar having a corresponding designating symbol, and also indicates that January 1, 1915, falls on the sixth day of the week. 105 The next symbol below the numeral "6" just mentioned in the January month column is "7" according to the above rule, which indicates the day in the week upon which the first of January falls in 1916. 110 According to this same rule, since 1916 is a leap year, the next numeral in the January

column will be "2", which indicates the day of the week upon which the first day of January 1917 falls. In a like manner the January column is continued as far as is desired. In this same manner the February month column is built up. The March month column for 1915 contains the numeral "2", indicating that the first day of March 1915 fell on the second day of the week. Since 1916 is a leap year, one numeral in the regular consecutive order of numerals is dropped between 1915 and 1916, which makes the next numeral in said March month column numeral "4". According to the above rule the next numeral in the March month column will be numeral "1", and so on until the column has been continued as far as desired. In the same manner the remaining nine month columns are built up.

If it is desired to ascertain a different day of the month than the first day, this is done by first determining the first day of the month in which the desired date falls. Then upon consulting the corresponding month calendar, the day of the week of the desired date will be found. As an instance of this, suppose it is desired to know the day of the week upon which the Fourth of July will be in 1920. The index is consulted in the 1920 year line, and in the July column we find the numeral "5", which indicates that the first day of July 1920 will be on Thursday, the fifth day of the week. Then upon consulting month calendar "5" we find the Fourth of July will be on Sunday. In this same manner the day of the week of any other desired date may be ascertained.

The index shown in the drawing extends from years "1880" to "1930" inclusive, but it will be apparent from the above that this index may be extended in either direction as far as desired, or the index may be shortened to indicate only one or more years, as may be desired.

While I have illustrated and described the preferred form of my invention, I do not desire to be limited to the precise details set forth, but desire to avail myself of such variations and changes as come within the scope of the appended claims.

I claim:

1. A calendar comprising thirteen par-

allel columns, one of the columns being a column of year dates arranged consecutively with the leap years displayed in a distinctive manner and the other twelve columns being month columns designated January to December month columns respectively and each being made up of seven recurring symbols which have a consecutive relation with each other and relate to the days of the week, said symbols being arranged in consecutive order in each month column except in the January and February month columns where one symbol is dropped from the consecutive order between each leap year and the year following such leap year and in each of the other ten month columns one symbol is dropped from the regular consecutive order between each leap year and the year previous to such leap year.

2. A calendar comprising seven month calendars each beginning on a different day of the week and having a designating symbol, said designating symbols having a consecutive orderly relation corresponding to the days of the week upon which the first days of the month calendars begin; and an index having a column of consecutive year dates with the leap years displayed in a distinctive manner and twelve month columns parallel with the year dates column and designated as January to December month columns respectively, each of the month columns being made up of symbols corresponding to the designating symbols of the month calendars and arranged in a consecutive order except in the January and February month columns where one symbol is dropped from the consecutive order between each leap year and the year following such leap year and in each of the other ten month columns one symbol is dropped from the regular consecutive order between each leap year and the year preceding such leap year.

In testimony whereof I have signed my name to this specification, in the presence of two subscribing witnesses, on this 2nd day of October, A. D. 1915.

EPHRAIM H. RODEN.
